SYSTEM FOR FILLING CONTAINERS

Edgar W. Bleam, Philadelphia, Pa., assignor to
 Stokes and Smith Company, Philadelphia, Pa.,
 a corporation of Pennsylvania

Application August 7, 1941, Serial No. 405,741

12 Claims. (Cl. 226—25)

My invention relates to systems for filling containers of paper, metal, glass, or other appropriate material and is particularly concerned with filling containers with powdered materials such as cocoa, talcum, flour, spices, soap powder, milk powder, and the like, or with free-flowing granular materials such as salt, sugar, and the like, all for brevity herein generically termed "powdered materials."

In accordance with one aspect of my invention, a charge of powdered material is introduced into a container by an auger, or equivalent, rotating during withdrawal of air from the container so to ensure the container shall receive and retain an accurately predetermined amount of the material, to ensure compactness or dense packing of the charge in the container, and to avoid the otherwise occurring escape of material with air forced out of the container counter-current through the incoming charge.

Further in accordance with another aspect of my invention, the aforesaid auger is rotated at constant speed for a fixed fraction of the machine cycle with provision of means, such as a variable speed transmission, for changing the length or duration of the machine cycle so to vary or predetermine the amounts of filling received by the containers for successive cycles of the machine.

Further in accordance with my invention, before removal of the filled container, screening, through which gas, generally air, has been withdrawn from the container, is subjected to a reverse puff of gas or air which clears the screen of powdered filling material clinging to it thus to return that material to the main body of filling in the container and to ensure proper exhaustion of the next container.

In accordance with one form of my invention, the container during filling is enclosed within a chamber, defined by relatively movable sealing members, within which the gas pressure is reduced during withdrawal of air from the container so to avoid its collapse by atmospheric pressure.

In accordance with another form of my invention suited for filling of bags, the bag to be filled is received by a pocket through whose apertured wall suction is applied to hold the bag distended for reception of the charge.

My invention further resides in the systems and in the features of construction and arrangement hereinafter described and claimed.

For an understanding of my invention and for the illustration of preferred forms thereof refer-

ence is made to the accompanying drawings, in which:

Fig. 1 is a perspective view of a complete filling machine.

Fig. 2, on enlarged scale and with parts broken away, shows in perspective the upper part of the machine shown in Fig. 1.

Fig. 3, on enlarged scale and in perspective, shows parts concealed in Fig. 1 by a cover plate.

Fig. 4, on enlarged scale and with parts broken away, illustrates the lower portion of the machine shown in Fig. 1.

Fig. 5, partly in section, illustrates elements of the machine of Fig. 1 concerned with exhaustion of air from the containers.

Fig. 5A, in perspective, shows the filling head of Fig. 5 inverted for illustration of features of its construction.

Fig. 5B is a fragmentary view with parts broken away to show further details of construction of the sealing head of Fig. 5A.

Fig. 6 is a front elevational view of valves and cam mechanism appearing in Fig. 5.

Fig. 7 is a table or timing chart referred to in the description.

Fig. 8 is a fragmentary view illustrating a modification of the filling head shown in Fig. 5.

Fig. 9 illustrates another modified form of filling head.

Fig. 10 is a perspective view of a bag.

Fig. 11, partly in section, is a detail view of a modified form of filling head suited for filling of bags.

Fig. 12, in section, is a fragmentary view illustrating another modified form of filling head.

Fig. 13 is a bottom plan view of the filling head of Fig. 12.

Fig. 14, diagrammatically and in perspective, shows significant elements of a full automatic filling machine embodying my invention.

In the particular embodiment of my invention shown in Fig. 1, the operator places the container C, exemplary of a can, jar, carton, or other container to be filled, upon the platform 1 below the

open discharge end of the hopper 2 which contains the filling to be introduced into the container. The pedal 3 is then momentarily depressed to initiate a cycle of operation of the machine during which the platform 1 is elevated

to bring the upper edge of the container C into sealing engagement with the under face of the suction head 4. While the container remains in elevated position with its interior thus isolated

from atmosphere, air is withdrawn therefrom by

the suction pump 5, or equivalent, whose connec-

tions to the suction head 4 include the hose 8 and control valves hereinafter discussed. During continued application of suction, filling is fed from hopper 2 through the tube 7 whose open, lower end, Fig. 5, for example, is in communication with the interior of the container.

Preferrably, the feed of powdered material into container C is effected by an auger 9 which closely fits the neck or discharge conduit 7 of hopper 2 and rotates therein for a fraction of each cycle of the machine. Upon conclusion of feed of filling to the container and before the end of the cycle of the machine, the suction is discontinued, and powdered filling which has been drawn against screen structure 105 of the suction head is blown therefrom back into the container.

After these operations have occurred, the platform 1 is automatically lowered to allow removal of the filled container C, so completing the cycle of operations of the machine. The operator then places another empty container upon platform 1 and again momentarily depresses clutch pedal 3 to initiate another cycle of the filling machine.

Referring for more detailed description of the machine to Figs. 2 and 3, the shaft 8 which intermittently drives the feed auger 9 extends upwardly through the table 10 within the enclosure afforded by one of the side frames 11. The gear 12, attached to the upper end of shaft 8, is connected to gear 13, secured to the upper end of the auger shaft 14, through the intermediate gear 15 rotatable upon the stub shaft 16 attached to and extending upwardly from the cross member 17 extending between the side frames 11.

The gear 18, rotatable in unison with gear 15, is in mesh with gear 19 secured to the upper end of sleeve 20, concentric with auger shaft 14 and to which is secured the agitator 21 provided to facilitate proper feed of powdered materials having strong tendency to pack.

By way of example, the speed of agitator 21 may be about 100 revolutions per minute whereas the speed of the auger is materially higher, for example 700 revolutions per minute.

To adapt the machine for use with different powdered materials and for a wide range of sizes of containers to be filled, the auger 9 and its sleeve 7 are replaceable by other augers and sleeves of different sizes. To facilitate removal of the auger, its connection to shaft 14 may be effected, as appears in Fig. 2, by a pin and bayonet slot connection.

The lower end of shaft 8 is connected, as by coupling 22, Fig. 3, to the driven shaft 23 of the combined brake and clutch unit 24 interposed between shaft 8 and the continuously rotating shaft 25 to which is attached the bevel gear 26 in mesh with bevel gear 27 of the clutch 28.

The yoke 29 for operating both the clutch 28 and the brake 30 is pivoted at 31 to one of the side frames 11 of the machine. The lugs 32 of the yoke 29 are received by a groove in the sleeve 33 so that upon upward movement of the arm or yoke 29 the plates 28a, 28b of the clutch 28, connected respectively to shaft 8 and to the continuously driven clutch element, are forced together into frictional driving engagement so to effect rotation of the feed auger 9; conversely, when the arm 29 is moved downwardly, the clutch plates are disengaged to disconnect shaft 25 from the auger 9 and the brake 30 is applied promptly to stop rotation of shaft 8.

The aforesaid movements of the control arm 29 are effected by the cam 34 attached to shaft

35 which, as hereinafter appears, makes one revolution for each cycle of the machine. The cam follower 36, engaged by cam 34, is carried by bar 37 having a guide slot 38 through which shaft 35 passes and pivotally connected at 39 to the lever 40 supported by bracket 41. The arm 40 is biased to its lowermost position by spring 42 connected between arm 40 and the hook 43 extending upwardly from the frame bracket 44 and preferably threaded to provide for adjustment of the spring tension.

The operating connection between arm 40 and the yoke 29 is afforded by a resilient link construction comprising the member 45 pivotally attached at its upper end to arm 40 and through the lower end of which slidably extends the rod 46, an extension of the member 47 pivotally mounted, as by pin 48, upon the yoke member 29. The spring 49, compressed between the lower end of member 45 and the abutment provided by washer 50 and nuts 51 on the upper end of the rod 46, limits or determines the pressure applied to the clutch plates when the arm 29 is moved in one direction to force the clutch plates into engagement and determines the pressure applied to the brake when arm 29 is moved in reverse direction.

To suit the machine for filling containers differing substantially in size, the cam 34 may be replaceable by cams of suitably different angular extents, or as shown, the cam 34 may be made of two or more segments, one attached to shaft 35, and the other segment or segments adjustably attached as by bolt and slot connections to the first segment so to allow variation of the fraction of the cycle for which the members 28a, 28b of clutch 28 are in engagement with one another.

Referring to Fig. 4, to the cam shaft 35 is attached the driven clutch member 52 upon which is pivotally mounted the clutch dog or pawl 53 biased by spring 54 toward engagement with the continuously rotating clutch member 55 attached to or integral with sprocket 56. When the pedal 3 is momentarily depressed to initiate a cycle of the machine, the latch 57, connected to treadle 3, as by link 58, is withdrawn from engagement with the clutch pawl 53 thus allowing the spring 54 to move the pawl into engagement with the continuously rotating clutch member 55. At the end of the cycle, one revolution of shaft 35, the pawl 53 re-engages the latch 57, which in the meantime has resumed its original position, and by it is moved, in opposition to spring 54, out of engagement with the driving clutch member 55.

The shaft 25 for driving the auger 9 through clutch 24 is driven continuously and at constant speed, as by motor 59 through the driving connection comprising pulley 60, belt 61 and pulley 62, whereas the shaft 35 is operated only intermittently, one revolution for each depression of the pedal 3, and at a speed which may be smoothly and finely varied, as by the Reeves-drive 63, Fig. 1, or equivalent speed-conversion mechanism, interposed between the one-cycle clutch 53, 55 and the continuously rotating shaft 25. Changing the ratio of the speeds of shaft 25 and the driven clutch member 55 increases or decreases the amount of filling fed to a container during a cycle of the machine; the rate of feed, since change of aforesaid ratio does not affect the speed of the auger 9, is constant and the fraction of the cycle for which the clutch 24 is engaged is constant for all settings of Reeves-drive 63 but by changing the speed-ratio of the Reeves-drive, the time elapsing from start to finish of each cycle is

correspondingly varied and consequently the number of revolution of auger 9 per cycle of the machine is changed.

Though any other suitable speed-conversion device or variable-speed transmission may be used, the change in aforesaid speed-ratio is effected, in the particular arrangement shown, by turning the hand wheel 64 to vary the angular position of arm 65 which carries the idler pulley 66; as arm 65 is depressed, Fig. 1, (moved in counter-clockwise direction about pivot 67) the belt 69 further forces apart the driving cones 69 in opposition to a biasing spring, not shown, so to reduce the ratio between the speeds of shaft 25 and sprocket 14 on shaft 67 respectively. Conversely as the arm 65 is raised the driving cones move closer together, effectively increasing the diameter of the driving pulley for belt 68 and so increasing the speed of rotation of clutch member 55.

This adjustment, which can be effected whenever necessary or desirable without interruption of operation of the machine, provides for very precise regulation of the amount of filling fed from the hopper for each cycle of the machine.

The driven shaft 10 of the speed-conversion mechanism 63 may be coupled to shaft 25 in any suitable manner, as by sprockets 71, 72 attached to shafts 25 and 10 respectively and connected by the chain 73. Similarly the driving shaft 67 of the speed-conversion mechanism may be provided with a sprocket 14 coupled to sprocket 56 of the one-cycle clutch 53, 55 by the chain 75.

The cam 76, Figs. 4-6, for controlling the reciprocation of the container-supporting platform 1 is carried by the one-cycle shaft 35. The arm 77 which carries the cam follower 78 is pivoted at 79 to the bracket 80 depending from the platform 10. Movement of arm 77 is communicated to plunger 81 by the link 82 pivotally connected at its lower end to arm 77 and at its upper end to the collar 83 attached to plunger 81. The spring 84 disposed about plunger 81 between collar 83 and the extension 85 of bracket 80 which serves as a guide for the lower end of plunger 81 biases the platform 1 to its uppermost position and determines the maximum pressure between the rim of the container C and the sealing ring 86, of rubber, such as Manhatten #00, or equivalent yielding material, suitably attached to the underface of the suction head 4. Cam 76 may be so shaped that, as appears from the timing chart Fig. 7, the platform or table 1 is allowed to rise to its uppermost position during about the first thirty degrees of the cycle of the machine and is returned by cam 76 to its lowermost position during the last thirty degrees of the machine's cycle. As shown in Figs. 5 and 6, cam 76 may comprise two segments one directly secured to shaft 35 as by a clamping screw and adjustably secured to the other segment by a bolt and slot connection.

The arrangement for withdrawing air from the interior of container C includes hose 6 connecting the suction head 4 to the inlet chamber 87A of the valve housing 87, hose 88 connecting the exhaust chamber 89 of the valve housing to the tank 90, and hose 91 connecting tank 90 to the intake 92 of the suction pump 5. The suction may be regulated by any conventional means exemplified by the pressure control valve 93; a negative pressure or vacuum corresponding with a column of about 15 inches of water has proved satisfactory.

The valve 94 controlling communication be-

tween the inlet chamber 87A and discharge chamber 89 is biased to closed position as by the spring 95. The cam 96 for controlling the movements of valve 94 is attached to the one-cycle shaft 35.

5 The bracket 97 extending from the valve casing 87 supports the rocker arm 98 whose upper end supports the cam follower 99 and whose lower end is adapted to engage and effect movement of the movable valve element 94. The cam 96 may, as indicated by the timing chart, Fig. 7, be constructed to open valve 94 at about the same time that the interior of the cam C is sealed to atmosphere by engagement of its rim by the sealing ring 86, to maintain valve 94 closed for withdrawal of air from the container for at least a substantial portion of the cycle during which the auger 9 is forcing material into the container and to open valve 94 to effect discontinuance of suction at suitable time before end of the cycle, for example, somewhat before or after rotation of the auger is interrupted by disengagement of the members of clutch 28, Fig. 3.

20 Referring particularly to Fig. 5, the suction head 4 may be detachably secured as by the bolts 100, to the flange 101 suitably held, as by welding or brazing, to the lower end of the filling tube 1. The main or body portion 102 of the suction head is provided with an opening or bore 103 in alignment with the tube 1 in effect to form a continuation thereof, and as shown in Fig. 5, the auger 9 may be of length sufficient to extend into opening or bore 103 which is preferably tapered very closely to approximate, at its lower or discharge end, the diameter of the feed auger.

25 The suction port 104 in the underface of head 4 may, as shown in Fig. 5A, be circular and substantially concentric with the bore 103. The screen 105, Figs. 5 and 5B, for preventing entry of the filling material into the suction port is held in place by the sealing rings 106, 107; as indicated in Fig. 5, the smaller or inner ring 106 may thread into the central opening 103 of the head, and the outer or larger ring may be held to the body portion 102 by screws 108. The mesh of 30 screen 105 is suitably fine to prevent passage therethrough of the filling; for example a mesh of 200 per inch or finer is suitable for talcum, powdered chocolate and the like.

35 In contrast with prior arrangements in which a charge of powdered filling is dumped into a container open to atmosphere, the filling discharged by auger 9 immediately settles without tendency to float or blow out of the container and densely packs without entrapment of any appreciable amount of air.

40 When, as desirable, the operations of filling and withdrawal of air overlap, some of the filling material collects upon the screen 105 and in the case of many materials, such as cocoa, sc 45 tightly packs it remains there even after suction is discontinued. To clear the screen and to ensure the material which has collected thereon is returned to the container as part of its contents, it is blown therefrom before the filled container is removed from platform 1. For that purpose, the valve housing 87 is provided with a second outlet chamber 109 either in communication with atmosphere or the exhaust 110 of the suction pump 5. The valve 111, Fig. 6, which controls 50 communication between the outlet chamber 109 and the inlet chamber 86 is biased to closed position, as by a spring not shown. The cam 112 for controlling the movements of valve 111 is attached to the one-cycle shaft 35 and during its 55 rotation effects movement of the rocker arm 113.

pivotedly supported by bracket 97 and having the cam follower 114 mounted upon its upper end in engagement with, or in the path of, cam 112. The lower end of arm 113 is disposed to engage the stem of the valve 111.

The cam 112 is so constructed and positioned on shaft 35 that, as shown by the timing chart Fig. 7, the valve 111 is opened for a brief period after rotation of the auger 9 has been interrupted. Opening of the valve causes an inrush or puff of air which blows the powdered filling clinging to the screen 105 back into the can C, or equivalent, so ensuring proper weight or quantity of filling in the can and cleaning the screen for proper exhaustion of the container next to be filled in the succeeding cycle of the machine.

Though my arrangement does not involve actual weighing of the charges of filling, the net weights of the successively filled containers nevertheless agree very closely; for example, charges of powdered filling introduced into a series of containers and intended to have a nominal magnitude of five pounds differ from that magnitude by not more than about one-half ounce, i. e., the accuracy is to within $\frac{1}{2}\%$ or better; more generally, for the range of from about one-half ounce per charge to ten pounds per charge, the accuracy is within 0.5% for the smaller weights and within one-quarter of an ounce for the larger weights. Furthermore, in practice this high degree of accuracy is obtained when the machine illustrated is operated to fill containers at the rate of about twenty-five to thirty per minute.

To accommodate the machine for containers of somewhat different heights, the suction head 4 may be provided, as shown in Fig. 8, with an adjustable ring 115 whose under face is recessed to receive the sealing ring 86. The ring 115 may be split to permit its adjustment axially of the suction head when the clamping screw 116 is loosened. Because the material is, as above stated, tightly packed under the combined influence of the auger and the vacuum and as between different containers uniformly packed, there is no need to provide for a substantial free space above the filling; consequently a smaller can than usual can be used and the sealing ring 115 set to be only slightly higher than the plane of the lower end of the feeding and packing auger 9.

When the walls of the containers are so thin or are of such material that they would be collapsed by atmospheric pressure during exhaustion of the containers, there may be utilized a modified arrangement, shown in Fig. 9, in which there is provided a sealing member or sleeve 117 which, when the platform 1A is in elevated position, defines a second chamber external to the container C1 and also subjected to suction thus to balance the pressures within and without the container C1. The sleeve 117 at its upper end closely fits or is sealed against the suction head 4; the lower edge of the sleeve is in alignment with a sealing ring 118, or other suitable sealing member, suitably attached to the platform 1A for sealing engagement with the ring 118 when the platform is raised to the position shown in Fig. 9 for filling of container C1.

The outer chamber defined by the container C1, sleeve 117, suction head 4 and platform 1A, is suitably connected to the suction hose 6 as by the fitting 119 which, as shown in Fig. 9, may also provide for connection of the suction port 104 with hose 6.

By slight modification of the platform and of

the suction head, Fig. 11, the apparatus may be adapted to fill bags of paper, tin-foil, or like material, including bags of the so-called square or self-opening type shown in Fig. 10.

- 5 Referring to Fig. 11, the outer clamping ring 107 of Fig. 5 is replaced by clamping ring 107B having a deep annular groove 120 for reception of the upper part of the bag C2 usually folded after introduction of filling to close the mouth 10 of the bag. The lower edge of rim 121 of the clamping ring 107B co-acts with a sealing ring 122 of rubber or other suitable yielding material to isolate from atmosphere the chamber defined by the interior of the container C2 and the groove 120. The ring 122 is carried by the channel member 123 which surrounds the container C2 and is supported by the upper ends of the sleeves 124, 125 which are suitably secured at their lower edges to the platform 1.
- 10 The sleeves 124 and 125, the channel member 123 and the platform 1 define a suction chamber 126 which surrounds the container C2. The outer sleeve 124 is peripherally continuous to isolate this chamber from atmosphere whereas 15 the inner sleeve 125 is provided with a multiplicity of perforations 127 through which suction is applied to expand the container C2 and hold it in shape for introduction of filling. The suction chamber 126 is connected to any suitable source 20 of suction, for example the suction pump 5, by the hose 6A and valve 94; preferably, the suction to the outer chamber 126 is controlled by a valve other than valve 94 to provide for supply of suction to chamber 126 before the platform 1 rises. 25 In either case, the operator need merely drop the bag C2 into the pocket defined by the inner sleeve 125 and then momentarily depresses the pedal 3 to initiate a cycle of the machine. Upon completion of the cycle, the operator lifts the 30 filled bag out of the pocket and replaces it by the empty bag next to be filled.
- 35 In the modification shown in Figs. 12 and 13, suited for filling cans which are substantially oval as well as of other cross-sectional shape, the large 40 sealing disc 86A, of rubber or equivalent, is received by a recess in plate 129 suitably fastened to the underside of the main or body member 102A of head 4. Through the central projecting portion 129 of plate 128 extend the discharge passage 103, forming a continuation of the bore of pipe 7 from the hopper 2, and the suction ports 104A in communication with suction ports 104 of head 102A and each covered with a fine screen 105A serving the purpose and having the characteristics of screen 105 of previously described 45 modifications.
- 50 With the system shown in Fig. 14, all operations are automatically performed; empty containers C are fed adjacent platform 1 by any suitable means such as the continuously moving conveyor belt 130 upon which they are kept in line by guide bars 131 terminating short of platform 1.
- 55 The empty containers are in turn pushed onto platform 1, or equivalent, into alignment with filling head 4 by the transfer member 132 which reciprocates to and from the position shown in Fig. 14. When moved to the right to that position, member 132 pushes from stop 3A onto platform 1 an empty container which displaces from the platform a filled container preferably transported away from the filling station by another conveyor such as the continuously moving belt 134 associated with guide bars 135. When transfer member 132 is moved to the left from the 60 position shown in Fig. 14, it permits the row of

empty containers to advance with belt 130 until the leading container is arrested by the stop 3A.

The reciprocation of transfer member 132 is effected by cam 138 on shaft 35B driven from motor 59 through the one-cycle clutch 53A, 55A which is tripped when stop 3A is engaged and moved by the leading empty container on belt 130 to effect, through link 58A, release of latch 61A from the pawl or dog 53A.

Upon shaft 35B, suitably driven from shaft 35C, as by sprockets 141, 142 and chain 143 and rotating one revolution for each cycle of clutch 53A, 55A, are also disposed the cam 76 for effecting reciprocation of platform 1 and the cams 96, 112 for controlling valves 94 and 111, all as previously herein described in connection with the modification shown in Figs. 1-7. However, cam 34 of the full automatic system, Fig. 14, is mounted upon another shaft, shaft 35A, driven from the continuously rotating shaft 25 through a second one-cycle clutch 137 whose driven pawl or dog 138 secured to shaft 35A is engaged by latch 139, at the end of each revolution of shaft 35A, and is moved thereby from engagement with the continuously rotating driving member 140 of the clutch. These clutch members remain out of engagement until at predetermined time in a revolution of one-cycle shaft 35A, the cam 145 trips latch 139 and so initiates a cycle of shaft 35A during which cam 34, as previously described in connection with Figs. 1-7, controls operation of feed auger 9 to force a charge of filling into a container on platform 1.

With the same high accuracy heretofore mentioned, the full automatic system of Fig. 14 can fill containers at the rate of about thirty per minute; correspondingly higher output is obtained when several such filling units are combined in a single machine, for example in manner generally similar to that shown in Figs. 5 and 6 of my United States Letters Patent 2,082,567.

For brevity in the appended claims, the term "air" includes air and gas or fluid other than air which may have been used for conditioning or treating the interior of the container or for conditioning or treating the filling material.

What I claim is:

1. A filling machine comprising an auger operable in each cycle of the machine to feed material into a container, means for driving said auger for a fixed fraction of each of successive cycles of the machine and at a speed which is fixed independently of the duration of aforesaid cycles, and means for varying the amounts of filling received by the containers comprising means adjustable to regulate the duration of the machine cycles.

2. A filling machine comprising an auger rotated in each cycle of the machine to feed powdered material into a container, means including a rotatable member for effecting rotation of said auger at fixed speed for a fixed fraction of each of successive cycles of the machine, and means for varying the amounts of filling received by the containers comprising a variable speed transmission between said rotatable member and a source of power effecting its rotation.

3. A filling machine comprising an auger rotated in each cycle of the machine to feed powdered material into a container, means including a rotatable member for effecting rotation of said auger at fixed speed for a fixed fraction of each of successive cycles of the machine, and means operable during continued operation of the machine to vary the amounts of filling received by

the containers comprising coupled rotating members connected respectively to said rotatable member and a source of power therefor, and means adjustable to vary the effective diameter of at least one of said members.

4. A filling machine comprising an auger for feeding powdered material into a container, a source of power, a clutch between said auger and said source of power, a rotatable control member effecting engagement of the members of said clutch for a predetermined fraction of each cycle of said machine, and means for varying the ratio of the extent of rotation of said auger to the extent of rotation of said control member comprising a variable speed transmission between said source of power and said control member.

5. A filling machine comprising an auger for feeding powdered material into a container, a source of power, a clutch between said auger and said source of power, a rotatable control member effecting during a fixed fraction of each revolution thereof engagement of the members of said clutch, and means for connecting said control member to said source of power independently of said clutch comprising in series between them a one-cycle clutch and a variable speed transmission.

6. A machine for filling collapsible containers comprising a head providing a passage for discharge of the filling, a platform for supporting a container during introduction of its filling, a sealing member surrounding said passage and coacting with the mouth of the container to isolate the interior thereof from atmosphere during filling, relatively movable sealing members surrounding the container during aforesaid introduction of its filling to define a chamber isolated from atmosphere and from the interior of said container, means for withdrawing air from the container during its reception of filling discharged from said passage, and means for preventing collapse of the container during aforesaid withdrawal of air therefrom comprising means for reducing the pressure in said chamber.

7. A machine for filling bags comprising apertured wall structure defining a pocket for receiving a bag to be filled, means for applying suction to side wall structure of the bag through said apertured wall structure to hold the bag distended, relatively movable sealing members coacting to isolate the interior of said bag from atmosphere, means for discharging filling material into the distended bag, and means for withdrawing air from the bag during filling thereof and while said suction means prevents its collapse.

8. Apparatus for filling a container with powdered material comprising a member extending downwardly into the container and having a passage through which the filling is introduced into the container, an auger extending to the discharge end of said passage for forcing said material into said container and contributing to dense packing of said material, one or more suction passages distinct from said first-named passage extending through said member for communication with the interior of the container and there contributing to the packing effect of said auger, and a sealing element surrounding said member and disposed to engage the mouth of the container substantially above the lower end of said member.

9. Apparatus for filling a container with powdered material comprising a member extending

downwardly into the container and having a passage through which the filling is introduced into the container, an auger extending to the discharge end of said passage for forcing said material into said container and contributing to dense packing of said material, one or more suction passages distinct from said first-named passage extending through said member for communication with the interior of the container and there contributing to the packing effect of said auger, a sealing element surrounding said member and disposed to engage the mouth of the container, a support for said container, and means for preventing collapse of the container by withdrawal of air therefrom through said suction passage or passages comprising a sleeve attached to said member and co-operating with said support to define a chamber enclosing said container, and a source of suction connected to said chamber.

10. Apparatus for filling a container with powdered material comprising a member extending downwardly into the container and having a passage through which the filling is introduced into the container, an auger extending to the discharge end of said passage for forcing said material into said container and contributing to dense packing of said material, one or more suction passages distinct from said first-named passage extending through said member for communication with the interior of the container and there contributing to the packing effect of said auger, a groove in the lower face of said member for reception of the upper portion of the wall structure of the container, and means for preventing collapse of the container by withdrawal of air therefrom comprising structure co-operating with said grooved member to define an inner chamber in which said container is disposed, and providing an outer chamber through which suction is applied to the exterior of the container.

11. Apparatus for delivering powdered material into a container and densely packing said material in the container by the combined in- 45

fluence of positive feed and vacuum, comprising a filling head co-acting with the mouth of the container to isolate its interior from atmosphere, an auger positively feeding a charge of said material into the container through a passage, in said head, whose discharge is continuously in free and open communication with said container, said auger extending at least to the mouth of said container and thereby positively feeding the charge immediately into said container, automatic means discontinuing feed of the charge into said container by said auger after a predetermined time, and a source of suction in communication with the interior of said container through a second passage, in said head, to effect, by the combined influence of said auger and suction, dense packing of the charge in said container.

12. Apparatus for delivering powdered material into a container and densely packing said material in the container by the combined influence of positive feed and vacuum, comprising a filling head co-acting with the mouth of the container to isolate its interior from atmosphere, an auger positively feeding a charge of said material into the container through a passage, in said head, whose discharge is continuously in free and open communication with said container, said auger extending at least to the mouth of said container and thereby positively feeding the charge immediately into said container, automatic means discontinuing feed of the charge into said container by said auger after a predetermined time, a source of suction in communication with the interior of said container through a second passage, in said head, to effect, by the combined influence of said auger and suction, dense packing of the charge in said container, a screen for said second passage disposed at substantially the level of the discharge end of said auger, and means for momentarily passing gas in reverse direction through said screen only after feed by said auger has ceased.
